UNITED STATES PATENT OFFICE.

WALTER J. WARDER, JR., OF CHICAGO, ILLINOIS, ASSIGNEE TO ROTH BROS., OF CHICAGO, ILLINOIS.

CONTROLLER.

No. 878,756.

Specification of Letters Patent.

Patented Feb. 11, 1908.

Application filed May 13, 1907. Serial No. 373,466.

To all whom it may concern:

Be it known that I, WALTER J. WARDER, Jr., a citizen of the United States of America, and a resident of Chicago, county of Cook, State of Illinois, have invented certain new and useful Improvements in Controllers, of which the following is a specification.

The main objects of this invention are to provide an improved form of starting or speed-controlling rheostat for electric motors, that may be safely intrusted to careless or inexperienced operators without danger of injury to the motor when starting the same and without danger of burning the rheostat contacts by arcing as when the controller arm stops in positions between successive contacts; to provide simple mechanism whereby an improved starter or controller of this character may be operated from a moderate distance as easily as by direct manipulation; to provide an improved form of releasing mechanism adapted to instantly return the controller arm to its "off" or initial position when there is "no voltage" in the motor circuit, and to provide simple mechanism for imparting a step by step movement to the controller arm and adapted when inactive to assume a position permitting the free return of the controller arm to its "off" position, through the action of such "no voltage" release. These objects are accomplished by the devices shown in the accompanying drawings, in which:

Figure 1 is a perspective of a controller constructed according to this invention and provided with an operating pedal, the motor being mounted on a pedestal inclosing the controller box. Fig. 2 is a diagram of the electrical connections of the controller and motor. Fig. 3 is a front elevation of the mechanical part of the controller. Fig. 4 is a side view of same, looking in the direction of arrow *a* in Fig. 3. Fig. 5 is a detail of a part shown in Fig. 3.

In Fig. 1, the pedestal 1 incloses the rheostat and also provides a support for the motor 2. The plate 3 is provided with a series of contact buttons 4, having connection with the rheostat elements in any desirable manner.

5 is the movable controller-member which makes contact with successive buttons 4. 6 is a catch for holding said controller-member in contact with any one of the buttons 4 until released as hereinafter described.

7 is an actuating member arranged to be oscillated by the operator and to impart a step-by-step movement to the controller-element, which thus rests for a short interval upon each contact-button successively when starting the motor.

8 is a mechanical trip or throw-off, adapted to disengage the catch 6 from the ratchet sector 12 to permit the controller-member to be thrown back to starting position by its spring 13. The actuating member 7 has a limited stroke of a certain normal length, but is capable of a short additional backward movement. When forced back by the operator so as to describe this extra movement, the member 7 causes the trip 8 to act on a lever 11 that carries the catch 6, with the result hereinbefore stated.

9 is an electro magnet which is desirably employed for holding the catch 6 in operative contact with the ratchet 12 while the controller-element is on any of the live contact buttons 4.

10 is a short-circuiting device for de-energizing or weakening the pull of the magnet 9 when the operator desires to stop the motor. This device is actuated by the same extra movement of the member 7 that trips the pawl-lever 11. By the action of the de-energizing device the trip does not have to overcome the attraction of the magnet 9.

In the construction shown, the controller-member is in the form of an arm 5, pivoted on a stud 14, and urged toward "off" position by a spring 13. Said arm carries the contact shoe 15 and is provided with a detent pawl 16, pivoted at 17 and urged to an extended position by a spring 18. A stop 19 prevents the pawl from swinging in one direction from the position shown. The hub 5' of the arm 5 is provided with a sector having ratchet teeth 12.

The actuating arm 7 is mounted to oscillate upon a stud 20, and carries at its outer end a curved ratchet 21, the teeth 22 of which face toward the pawl 16 and are adapted to engage the same when said arm is moved forward. The position of the controller-arm 5 at the time, determines which of the teeth 22 will engage the pawl thereof. This operation is due to the relative positions of the pivots 20 and 14. The path of movement of any tooth 22 is along but not parallel with that of the pawl 16. When the arm 7 is moved to the right or forward, the teeth 22

move inwardly toward the path of the pawl 16, though in a general direction along said path.

The arrangement of the teeth is such that 5 they stand at equal distances from the center of rotation of the controller arm 5 when the part which carries said teeth is in its normal position (as shown). The result of this construction is hereinafter described.

10 The first tooth 22' is made sufficiently long to engage the pawl 16 when the arm 7 is in its initial position.

The ratchet 21, or arm 7, may be provided with a handle. But in cases where it is desirable to operate the controller from a distance, a pedal lever 23 is set up at the desired point and is connected to said arm by a rod 24. The lever 23 as shown is mounted on the floor and is in the form of a bell-crank provided with pedals 25 and 41. The actuating member 7 is urged toward its normal position by a spring 26, which therefore actuates the connecting rod 24 in one direction; so that, excepting as hereinafter described, the 20 operator has only to move the lever 23 in one direction.

The forward stroke of the arm 7 is limited by a stop 27, rigidly held by the plate 3. The backward stroke of said arm is normally 30 limited by a spring stop 28 which is struck by a lug 29. This spring is adjustable so as to balance the spring 26 when the shoe is on the "off" button.

The holding magnet 9 has pole pieces 35 and the lever 11, or at least the upper part thereof, is made of soft iron. The holding pawl 6 is preferably a spring mounted upon this lever.

The trip or throw-off, 8, is carried by the 40 arm 7, and is so arranged that by moving about the pivot 20, it will disengage the pawl 6 from the teeth 12.

The deenergizing device 10 comprises a pair of spring contact pieces normally out of 45 contact with and insulated from each other.

The arm 7 carries a button 32, of insulating material, held in position to bring the parts 10 into contact with each other when the hereinbefore mentioned extra backward 50 movement is imparted to said arm. The members 10 are connected by taps 33 to the respective leads of the magnet. One of the magnet leads is connected to the first or lowest-speed button 4, and the other lead is connected to the motor by wire 34. The other 55 motor terminals are connected to the last contact button at 35 and to the switch 36, by wires 37 and 38 respectively. From the other pole of the switch a wire 39 leads to the 60 controller-arm 5.

The operation of the controller when constructed as shown is as follows: The arm 5 being normally at "off" position, the operator depresses the pedal 25 a number of 65 times, it being lifted after each depression

by the spring 26 of arm 7. If the device is a "starting box" the lever 25 is operated until the motor has attained its full speed, the arm 5 stopping on the last button. If a running rheostat is provided, the controller-arm may be stopped on any intermediate button for getting the required speed of the motor. As soon as the arm 5 touches the first live button 4, the magnet 9 is energized and draws up the lever 11, thereby holding 75 the pawl 6 in engagement with ratchet sector 12. The controller-arm is thus held against backward movement until the operator wishes to stop the motor. To stop the motor, the operator presses the foot-piece 41, thereby pushing on the connecting rod 24, and moving the arm 7 to the left against the spring 28. This movement also causes the contact pieces 10 to engage so as to short-circuit the magnet 9, and simultaneously 80 causes the trip 8 to move lever 11 and throw off the pawl 6. The teeth of the ratchet 12 are preferably of such form that the pawl 6 will not hold the arm 5 when there is "no voltage" on account of opening the main switch 36 or otherwise, but the mechanical trip 8 is also provided to prevent the possibility of the catch holding on account of residual magnetism after the current is cut off. The spring 13 throws the controller-arm 5 quickly back to "off" position. During the operation of the actuating member 7, in starting the motor, the tooth 22' will be the first one to engage the pawl 16; on the back stroke said pawl will yield to let the second tooth pass. On the next forward stroke the second tooth will engage the pawl, which will then yield to let the third tooth pass on the return stroke, and so on until the 90 arm 5 has been stepped up to the desired 100 position. When this arm is released, it will fly back without the pawl touching any of the teeth 22, owing to the fact that the points of all said teeth lie beyond the path of the tip of said pawl when the arm 7 is at normal 105 position.

What I claim as my invention and desire to secure by Letters Patent is:

1. In a starter or controller for electric motors, the combination of a movable controller member, a movable actuating member adapted to shift said controller member in one direction by its normal stroke and having a normal return stroke and being capable of extra movement at the end of its 115 normal return stroke, means for holding said controller member in different positions, and means actuated through said extra movement for permitting the controller member to return to starting position.

2. In a device of the class described, the combination of a movable controller member, a movable actuating member adapted through a back and forth movement to advance said controller member to successive 120 125 positions.

- positions, an operating member located at a distance from the controller member and connected with said actuating member for moving it, and means actuated by said operating member for returning said controller member to its initial position. 5
3. The combination with a motor controller comprising a pivoted controller-arm, a movable actuating member adapted through a back and forth movement to advance the controller-arm to successive positions, of an operating member located as a distance from the controller, a connection between said operating member and said movable member, and means adapted to return said controller-arm to its initial position through a certain movement of said operating member. 10
4. In a starter or controller for electric motors, a pivoted controller-element, a swinging actuating-arm provided with means for moving the controller element when moved in one direction, said means being normally inoperative in the reverse direction, mechanical means for swinging the actuating-arm to and fro, and means for returning the controller element to a certain initial position through a certain movement of said actuating-arm. 15
5. In a starter or controller for electric motors, a pivoted controller-element, a swinging actuating-arm provided with means for moving the controller element when moved in one direction, said means being normally inoperative in the reverse direction, means for holding the controller-element in different positions, mechanical means for swinging the actuating-arm to and fro, and means for returning the controller-element to a certain initial position through a certain movement 20 of said actuating-arm. 30
6. In a starter or controller for electric motors, the combination of a pivoted controller-arm, a pivoted actuating arm adapted to shift the controller-arm in one direction, means for holding the controller-arm in different positions during the return movement of the actuating arm, and means for releasing said holding means through a certain movement of said actuating arm. 45
- 50 7. In a starter or controller for electric motors, the combination of a pivoted controller-arm, a pivoted actuating arm adapted to shift the controller-arm in one direction, electro-magnetic means for holding the controller-arm in different positions during the return movement of the actuating arm, and means for releasing said holding means through a certain movement of said actuating arm.
- 60 8. In a starter or controller for electric motors, the combination of a movable controller member normally urged toward a certain initial position, a movable actuating member adapted to shift said controller-member in one direction and having a normal return stroke and being capable of extra movement at the end of its normal return stroke, means for holding said controller-member in different positions, and means actuated through said extra movement for releasing said holding means. 70
9. In a starter or controller for electric motors the combination of a pivoted controller-arm, a movable member adapted to shift said arm in one direction, and adapted to move in the reverse direction without shifting said arm, yielding means normally limiting the return stroke of said member, means for holding the controller-arm in different positions, and means actuated by movement of said member against said yielding means for releasing said holding means. 75
10. In a starter or controller for electric motors, the combination of a pivoted controller-arm, provided with a pawl, an actuating arm provided with a series of projections adapted to successively engage said pawl through successive backward and forward movements of said actuating arm and thereby advance the controller-arm in one direction only, and means for holding said controller-arm in different positions. 80
11. In a starter or controller for electric motors, the combination of a pivoted controller-arm, provided with a pawl, an actuating arm provided with a series of projections adapted to successively engage said pawl through successive backward and forward movements of said actuating arm, and thereby advance the controller-arm in one direction only, said actuating arm having a normal return stroke and being capable of extra movement at the end of its normal return stroke, means for holding the controller-arm in different positions, and means actuated by said extra movement of the actuating arm for releasing said holding means. 85
12. In a starter or controller for electric motors, the combination of a pivoted controller-arm, a movable member adapted to shift said arm when moved in one direction and to pass without moving said arm in the reverse direction, said member having a normal return stroke and being capable of continued movement beyond its normal return stroke, a catch for holding said arm in different positions, an electro magnet for holding said catch in operative position, and means actuated by said continued movement of said actuating member for deenergizing said magnet and releasing the controller-arm. 90
13. In a starter or controller for electric motors, the combination of a controller-arm having a pivot; an actuating arm having a pivot; said pivots being out of axial alignment; said actuating arm being movable to and fro; a curved ratchet carried by said actuating arm, the teeth of said ratchet being substantially equi-distant from the first pivot. 100

when the actuating arm is in its normal position; the controller-arm being provided with a pawl adapted to be engaged by said teeth successively whereby the controller-arm may be advanced to successive positions by oscillations of the actuating arm, and free to return to "off" position when the actuating arm is in its normal position.

14. In a starter or controller for electric motors, the combination of a series of contact points, a controller-element movable along said contact points, a movable actuating member adapted by to-and-fro movement to advance said controller-element to successive positions, said controller element controlling the speed of the motor, means for holding the controller element in each of said successive positions during return movements of the actuating member, and means actuated through a certain movement of said actuating member for releasing said holding means.

15. In a starter or controller for electric motors, the combination of a series of contact points, a controller-element movable along said contact points, an actuating member having forward and backward movement, a yielding stop to limit said backward movement, said actuating member being adapted to move the controller-element into successive positions when moved back and forth, means for holding the controller-element in each of its successive positions during backward movements of the actuating member, and means actuated by moving the actuating member and yielding stop backward, for permitting the controller-element to return to its initial position.

16. In a starter or controller for electric motors, the combination of a pivoted controller arm, a pivoted actuating arm, one of said arms having thereon a pawl, the other of said arms having thereon a series of ratchet teeth adapted to successively engage said pawl through successive backward and forward movements of said actuating arm and thereby advance said controller arm to successive positions, said pawl being adapted to yield to permit the return movement of said actuating arm without shifting said controller arm, and means for holding said controller-arm in its successive positions, and adapted to be released by a certain movement of said actuating arm.

17. In a starter or controller for electric motors, the combination of a pivoted controller arm, a pivoted actuating arm, one of said arms having thereon a pawl, the other of said arms having thereon a series of ratchet teeth adapted to successively engage said pawl through successive backward and forward movements of said actuating arm and thereby advance said controller arm to successive positions, said pawl being adapted to yield to permit the return movement of said

actuating arm without shifting said controller arm, said arms being pivoted on separate axes and said actuating arm being arranged to swing to such position as to permit said controller arm to swing freely to its initial position without engagement of said pawl and ratchet teeth.

18. In a device of the class described, the combination of a movable controller member, a movable actuating member adapted through a backward and forward movement to advance said controller member, one of said members having thereon a series of teeth and the other member having thereon a detent to resist relative movement of said members in one direction and freely permit such relative movement in the opposite direction, the respective paths of movement of said detent and ratchet teeth being at an angle to each other, whereby when said actuating member is in a certain position, said controller member will be free to return to its initial position without resistance by said detent and ratchet teeth.

19. In a device of the class described, the combination of a series of contact points, a controller member movable into contact with successive contact points, an actuating member adapted through forward and backward movement to advance said controller member along said series of contact points, a catch adapted to hold said controller member at each of said contact points during the return movement of said actuating member, an electro magnet adapted to hold said catch in position for holding said controller member against return movement and adapted when deenergized to release said catch and permit said member to return to its initial position, and means normally urging said controller member toward such initial position.

20. In a device of the class described, the combination of a series of contact points, a controller member movable into contact with successive contact points, an actuating member adapted through forward and backward movement to advance said controller member along said series of contact points, a catch adapted to hold said controller member at each of said contact points during the return movement of said actuating member, an electro magnet adapted to hold said catch into position for holding said controller member against return movement and adapted when deenergized to release said catch and permit said member to return to its initial position, means normally urging said controller member toward such initial position, and a shunt circuit short-circuiting the windings of said magnet and adapted to be closed through a certain movement of said actuating member for deenergizing the magnet and releasing the catch.

21. In a device of the class described, the combination of a movable controller mem-

ber adapted to vary a resistance, an actuating member adapted by repeated movements to advance said controller member step by step, and means actuated by a certain movement of said actuating member for causing said controller member to return to its initial position.

22. In a device of the class described, the combination of a movable controller member adapted to vary a resistance, a reciprocative member adapted by reciprocation to advance said controller member step by step, and means actuated by a certain movement of said actuating member for causing said controller member to return to its initial position.

23. In a starter or controller for electric motors, the combination of a movable controller member, a movable actuating member adapted through repeated movements to shift said controller member step by step in one direction, means for holding said controller member in its successive positions,

said actuating member being movable to a position clear of the path of said controller member and means adapted to release said holding means through the act of moving said actuating member to such position clear of said path.

24. In a starter or controller for electric motors, the combination of a line circuit, a movable controller member, a movable actuating member adapted through repeated movements to shift said controller member step by step in one direction, and magnetic means for holding said controller member in different positions and adapted through a drop in the voltage in the line circuit to release said controller member.

Signed at Chicago this 8th day of May, 40
